UNITED STATES PATENT OFFICE.

CORNELIUS J. BROSNAN, OF SPRINGFIELD, MASSACHUSETTS, ASSIGNOR,
BY MESNE ASSIGNMENTS, TO O. A. MILLER TREEING MACHINE COMPANY,
OF PORTLAND, MAINE, A CORPORATION OF MAINE.

SHOE-HOLDER.

No. 838,234.

Specification of Letters Patent.

Patented Dec. 11, 1906.

Application filed January 15, 1902. Serial No. 89,802.

To all whom it may concern:

Be it known that I, CORNELIUS J. BROSNAN, of Springfield, in the county of Hampden, and State of Massachusetts, have invented certain new and useful Improvements in Shoe-Holders, of which the following is a specification.

This invention relates to holders for supporting boots and shoes while the same are being cleaned and polished; and it has especial reference to holders intended for household use to enable the owner of a pair of boots or shoes to conveniently clean and dress the same.

The invention consists in the improvements which I will now proceed to describe and claim.

Of the accompanying drawings, forming a part of this specification, Figure 1 represents a side elevation of a shoe-holder embodying my invention. Fig. 2 represents a top view of the same. Fig. 3 represents a perspective view. Fig. 4 represents a section on line 4 4 of Fig. 1. Figs. 5 and 6 represent perspective views of the two parts or sections of the guide member of the telescopic arm hereinafter referred to.

The same characters of reference indicate the same parts in all the figures.

My improved shoe-holder comprises a telescopic arm composed of a guide member *a*, adapted for connection with a fixed support, such as a bracket *b*, affixed to a wall or other vertical support, and a sliding member *c*, which is movable in or upon the guide member *a* in such manner that the arm formed by the two members can be lengthened and shortened as the operator may desire. The guide member *a* is provided at its outer end portion with a heel-engaging shank *d*, which preferably projects downwardly from the member *a* and is formed to enter and conform to the shape of the interior of the heel portion of a boot or shoe upper, as indicated in Fig. 1. The sliding member *c* is provided with a last-holding shank *e*, which projects in the same general direction as the shank *d* and is adapted to extend into the boot or shoe upper between the heel and toe portions thereof, said shank *e* having means for detachably engaging and holding a fore-part last or block *f*, formed to enter and fit the fore part of the boot or shoe upper. One of

the members of the telescopic arm, preferably the guide member *a*, is provided with a ratchet *g*, and the other member, preferably the sliding member *c*, is provided with a pawl *h*, adapted to engage the teeth of the ratchet *g*, the said ratchet and pawl being arranged to permit any desired degree of separation between the shanks *d* and *e* and to prevent the shank *e* and the last *f* thereof from moving backwardly toward the heel-engaging shank *d*. It will be seen, therefore, that when the last *f* is engaged with the shank *e* and the latter is moved backward into close proximity to the shank *d* a boot or shoe can be readily placed upon the last and the shank *d* and can be firmly secured by moving the shank *e* and the last *f* outwardly until the last has a firm bearing in the toe portion of the upper and the shank *d* a firm bearing in the heel portion of the upper, this engagement of the last and the shank *d* being retained by the ratchet *g* and the pawl *h*.

The guide member *a* of the telescopic arm is preferably made in two longitudinal sections 2 and 3, which are grooved or recessed at their inner sides to form a chamber 4, Fig. 4, which receives and guides the sliding member *c*. The said sections 2 and 3 are connected by suitable means, preferably by dovetail tongues 5 5, formed on the sections 2, and dovetail grooves 6 6, formed in the section 3 and receiving the tongues 5, said tongues and grooves being arranged at the outer end portion of the arm member *a*, and a single bolt or rivet 7 extending through the sections 2 3 at the inner portion of the arm member *a*. The heel-engaging shank *d* is formed on one of the sections of the member *a*, preferably the section 3. The inner ends of the sections 2 and 3 are provided with webs or flanges 8 8, which collectively constitute a coupling member adapted to engage ears 9 9 on the bracket *b*, said parts 8 and 9 being preferably formed so that the telescopic arm can be readily applied to and removed from the bracket *b*. The sliding member *c* is provided with a handle 10 to facilitate its adjustment, the base of said handle preferably serving as an ear to which the pawl *h* is pivoted. The pawl has a handle *h'*, which when the pawl is in the position shown in Fig. 1 is arranged to be yieldingly held and to confine the pawl in said position

by the lower finger of the hand which grasps the handle 10, the back of the finger bearing yieldingly against the handle and acting to keep the pawl in yielding engagement with 5 the ratchet.

The last-supporting shank *e* is provided with a forwardly-extending finger *e'*, on the front end of which is formed an upwardly-projecting stud *e*².

10 *e*³ is a stud that projects forward from the front side of the shank *e* in the same direction as the finger *e'*.

The last *f* is provided in the bottom of its rear portion with a longitudinal slot *f'*, 15 formed to receive the finger *e'*, and with sockets *f*² *f*³, formed, respectively, to receive the studs *e*² and *e*³.

The above-described means for connecting the last with the shank *e* enables the last to 20 be quickly applied and removed.

j represents a chock or movable abutment which is movable upon the shank *e* and is adapted to be interposed between the front side of said shank and the rear end of the 25 last *f*, as shown in Fig. 1, to prevent backward movement of the last. When the chock is thus adjusted, the last is rigidly held by the conjoint action of the finger *e'*, studs *e*² *e*³, and chock *j*. When the chock is 30 removed from between the shank *e* and the rear end of the last, the latter can be readily removed from the shank *e* by tipping its toe portion upwardly. Provision is thus made for using lasts of different sizes and shapes 35 interchangeably.

It will be seen that the two-part construction of the arm member *a* enables said arm to be cheaply made by casting said parts and then assembling the castings, no coring 40 being required in making the castings.

It will be seen that the member *a* and its shank *d* together constitute a fixed elbow-shaped arm, one part of which is a guide, and that the member *c* and its shank *e* together 45 constitute a movable elbow-shaped arm, one part of which is a slide which is movable on said guide. The pawl and ratchet constitute an effective means for preventing backward movement of one arm 50 relatively to the other.

Having thus explained the nature of my invention and described a way of constructing and using the same, though without attempting to set forth all the forms in which 55 it may be made or all the modes of its use, what I claim, and desire to secure by Letters Patent, is—

1. A boot or shoe holder having in combination a slide, provided with means for supporting a fore-part last, and a guiding member composed of two longitudinal sections internally recessed to guide said slide, and provided with connecting means, one of said sections having a heel-engaging shank. 60

65 2. A boot or shoe holder having in combi-

nation a slide provided with means for supporting a fore-part last, and a guiding member composed of two longitudinal sections internally recessed to guide said slide, and provided at their outer portions with interlocking dovetail tongues and recesses, and at their inner portions with a connecting bolt or rivet. 70

3. A boot or shoe holder having in combination a slide provided with means for supporting a fore-part last, and a guiding member composed of two longitudinal sections internally recessed to guide said slide and provided with connecting means, said sections having webs or flanges at their inner 80 ends collectively forming a coupling member adapted for engagement with a fixed supporting member. 75

4. A boot or shoe holder of the character specified having a guiding member provided 85 with means for engaging the heel portion of an upper, a slide engaged with the guiding-arm member and provided with a shank adapted to enter the upper between the heel and toe portions projecting studs on said 90 shank adapted to engage complementary recesses formed in a fore-part last and a sliding chock carried by said shank and adapted to coöperate with said studs for locking the last in position. 95

5. A boot or shoe holder of the character specified, comprising an arm member provided with means for engaging the heel portion of an upper, and a second arm member engaged with the first-mentioned arm member and provided with a shank adapted to enter the upper between the heel and toe portions, a forwardly-projecting stud on said shank, a forwardly-projecting finger below said stud, and an upwardly-projecting 100 stud on said finger, said studs and finger being adapted to engage a fore-part last. 105

6. In a boot or shoe holder of the character specified, a fore-part last having a longitudinally-extending slot in its bottom portion extending forward from the rear end of the last, a socket extending upwardly from the forward portion of said slot, and a socket extending horizontally into the rear end of the last above the slot, said slot and 110 sockets being adapted for engagement with complementary portions formed on a supporting member. 115

7. A boot or shoe holder of the character specified, comprising a guiding telescopic 120 arm member having a ratchet and a heel-engaging shank, a sliding telescopic arm member having a last-engaging shank, and a handle 10 projecting upwardly beside the ratchet, and a pawl pivoted to said sliding member 125 and having a handle *h* arranged as described relatively to the handle 10.

8. In a shoe-holding device, the combination with an arm provided with an extension having an upwardly-extending stud, said 130

arm having a forwardly-projecting stud near its junction with the said extension, of a detachable fore-part last having a groove at its rear arranged centrally of its bottom 5 and provided with a socket leading from the forward portion of the groove and with a socket at its rear end above said groove.

9. A boot or shoe holder comprising a fixed guide having a ratchet and an arm 10 formed to bear on the interior of the heel portion of a boot or shoe, a slide engaged with and movable on said guide and having an arm formed to enter the fore part of a boot or shoe, said arm being provided with a shoe- 15 supporting form, a handle on said slide and

a pawl pivoted to the slide and having a handle which is arranged to be controlled by the operator's hand when the handle is grasped.

10. A boot or shoe form shaped to enter the fore part of an upper and having a slot 20 and a socket in its bottom, and a socket above said slot, said slot and sockets being arranged to receive complemental portions formed on a holder.

In testimony whereof I have affixed my 25 signature in presence of two witnesses.

CORNELIUS J. BROSnan.

Witnesses:

E. BATCHELDER,
P. W. PEZZETTI.

It is hereby certified that in Letters Patent No. 838,234, granted December 11, 1906, upon the application of Cornelius J. Brosnan, of Springfield, Massachusetts, for an improvement in "Shoe-Holders," errors occur in the printed specification requiring correction, as follows: In line 83, page 1, the word "sections" should read *section*, and in line 90, page 2, a comma should be inserted after the word "portions"; and that the said Letters Patent should be read with these corrections therein that the same may conform to the record of the case in the Patent Office.

Signed and sealed this 29th day of January, A. D., 1907.

[SEAL.]

F. I. ALLEN,
Commissioner of Patents.
